UNITED STATES PATENT OFFICE.

VICTOR LEE EMERSON, OF ALEXANDRIA, VIRGINIA, ASSIGNOR TO THE EMERSON
ENGINEERING COMPANY, A CORPORATION OF DELAWARE.

DESIGN FOR AN AUTOMOBILE-RADIATOR.

50,776.

Specification for Design.

Patented May 15, 1917.

Application filed February 10, 1916. Serial No. 77,536. Term of patent 14 years.

To all whom it may concern:

Be it known that I, VICTOR LEE EMERSON, a citizen of the United States, residing at 21 Rosemont avenue, Alexandria, Virginia, have invented a certain new, original, and ornamental Design for Automobile-Radiators, of which the following is a specification.

In the accompanying drawings which form a part of this specification, Figure 1 is a front view of a radiator and Fig. 2 a side view of the same, showing my new design.

I claim:

The ornamental design for an automobile radiator as shown.

In testimony whereof, I, VICTOR LEE EMERSON have signed my name to this specification in the presence of two subscribing witnesses, this third day of Feb. 1916.

VICTOR LEE EMERSON.

Witnesses:

CAROLINE V. EMERSON,
MARGARET V. EMERSON.
